UNITED STATES PATENT OFFICE.

WILLIAM H. GRINDLEY, OF CONGLETON, ENGLAND, ASSIGNOR TO WILLIAM S. PITCIARN, OF NEW YORK, N. Y.

DESIGN FOR A EWER.

SPECIFICATION forming part of Design No. 31,739, dated October 31, 1899.

Application filed September 29, 1899. Serial No. 732,114. Term of patent 31 years.

To all whom it may concern:

Be it known that I, WILLIAM H. GRINDLEY, a subject of the Queen of Great Britain, residing at Congleton, county of Chester, England, have invented a new and original Design for a Ewer; and I do declare the following to be a full, clear, and exact description of the same, reference being had to the accompanying drawings, which form a part hereof.

10 In the drawings, Figure 1 is a side view of a ewer embodying my design, and Fig. 2 is a top view of the same.

15 The leading features of my design are as follows: The body of the ewer is of a squat form, tapering from a cylindrical neck in a parabolic curve to the foot, which is short and also cylindrical. The lip or spout springs abruptly forward and upward from the neck,

and the whole is provided with a handle embossed with a tulip-bud. On each side of the 20 body is displayed an embossed group of tulips springing from the foot of the ewer and consisting of flowers and broad-bladed flat leaves. The neck is provided with an embossed representation of a tulip on each side, each being horizontally placed.

What I claim is—

The design for a ewer substantially as shown and described.

In witness whereof I have signed this specification, this 19th day of September, 1899, in the presence of two subscribing witnesses.

WILLIAM H. GRINDLEY.

Witnesses:

JOHN H. COPESTAKE,
THOMAS W. GALLIMORE.
